[57] CLAIM

The ornamental design for a sand and water playbox, as shown and described.

DESCRIPTION

FIG. 1 is a front and right side perspective view of a sand and water playbox showing my new design;
FIG. 2 is a rear elevational view;
FIG. 3 is a top plan view;
FIG. 4 is a right side elevational view, the left side having a mirror image thereof;
FIG. 5 is a front elevational view, and
FIG. 6 is a bottom plan view thereof.
FIGS. 2-6 have been shown on an enlarged scale with respect to FIG. 1.

FIG.1.

FIG.2.

FIG. 3.

FIG. 4.

FIG. 5.

FIG. 6.
